LLOYD L. DAVIS, OF HOPEDALE, MASSACHUSETTS, ASSIGNOR TO DRAPER CORPORATION, OF HOPEDALE, MASSACHUSETTS, A CORPORATION OF MAINE

REED POSITIONING DEVICE FOR LOOMS

Application filed May 2, 1931. Serial No. 534,471.

This invention relates to looms and is more particularly directed to a reed positioning device for controlling the position of the reed relative to the fell of the cloth.

- 5 As is well known by those familiar with weaving the position of the fell of the cloth will vary from time to time and yet in order to make perfect cloth filling or weft threads should be beaten uniformly to the fell of the cloth. These variations of the fell of the cloth may occur when making mechanical adjustments to the loom or removing filling, which may have been improperly laid, or it may occur from many other causes, such for 10 instance, as failure of the shuttle to lay filling properly in the shed. Should the shuttle have a trailing end of filling sufficient in length to act upon the weft fork or tilt it, the loom will continue to run, the cloth be 15 taken up and yet no filling be laid completely in the shed. These conditions would destroy the relation between the reed and the fell of the cloth, so that thin places are liable to occur, and imperfect cloth be woven.
- 20 Heretofore it has been proposed to avoid the above defects in the cloth by causing loom stoppage when a thin place occurs, but this results in decreased product and is often unsatisfactory.
- 25 One of the objects of the present invention is to provide means for regulating or controlling the position of the reed relative to the fell of the cloth during the beat up regardless of variations in the position of the fell, so 30 that the beat up action of the reed shall continue uniform throughout the loom operation and beat each filling thread properly to place at the fell of the cloth.

- 35 In the ordinary type of loom the lay has a uniform beat up movement, but inasmuch as the fell of the cloth may vary in position, the filling threads may not be beaten to place uniformly and so a further object of the invention is to provide a reed positioning device controlled by means initially operated by engagement with the fell of the cloth during beat up to maintain a proper relation between the reed and the fell of the cloth.
- 40 The invention and novel features thereof

will best be made clear from the following description and accompanying drawings of one good form thereof.

In the drawings:

Fig. 1 is a vertical section through the lay showing the latter by full lines in a back position and by dotted lines in a frontward position during weaving and following beat up movement; and

Fig. 2 is a front view of a portion of the lay with parts broken away showing the present invention.

The lay beam 1 is mounted upon the usual lay swords 2 and is actuated by a pitman 3 as usual, and extending upwardly from the lay swords are the end members 4.

Secured to the top portion of the end members 4 is a bracket 5 which may be secured to the end members by suitable bolts 6 and between the brackets 5, one at each side of the lay, is pivotally secured the upper portion or hand rail of the reed. As shown in the present instance of the invention the bracket 5 is provided with a projection or lug 7 and the back stay bracket 8 of the reed is similarly provided with a lug 9 which may be conveniently formed on an adjustable member 10, one at each side of the reed.

As shown, the adjustable member 10 may be secured to the hand rail 11 by means of a bolt passing through the member 10 which is provided with a slot or opening 13 for adjusting purposes. Passing through the lug or projection 7 and the lug 9 on the member 10 is a stud 14, which serves as a pivotal mounting for the upper portion of the reed or hand rail 11, the result being that the reed is pivotally supported at its upper portion for swinging movement relative to the lay. The construction described forms one good practical form of pivotally supporting the reed at its upper portion, but the details thereof may be variously contrived, the essentials being that the reed is mounted at its upper portion for pivotal movement in a direction towards and from the fell of the cloth.

The upper portion of the reed 15 may be held in the hand rail 11 in any suitable manner, but as hereinbefore shown, the upper

portion of the reed is held in a slot or opening 16 of the hand rail.

The lower portion 17 of the reed 15 is held in a bar or back stay 18, which is it-
5 self mounted for movement towards and from the fell of the cloth in a recess 19 formed in the lay beam 1.

Secured to the back stay 18 is a downwardly extending arm 20 which may be conveniently secured to the back stay by means of bolts or screws 21, and at the lower end of the arm 20 are a series of teeth 22, which engage a worm 23 mounted on the lay.

In the present instance of the invention 15 the lay beam has secured to it a bracket 24 by means of the bolts 25 and extending downwardly from the bracket is a bearing member 26, which supports the shaft 27 of the worm 23, the construction being such that 20 the worm may be turned relative to the bearing 26. As shown, the shaft 27 is secured in fixed position by a bolt 28 and the worm 23 rotates upon the shaft 27.

At the back portion of the shaft 27 is a 25 fixed collar 29, between which and the worm is an eccentric arm or crank member 30 secured to the worm 23, the construction being such that should the crank member 30 be turned about the shaft 27 the worm will be 30 correspondingly moved.

Secured to the crank member 30 at 31 is the upwardly extending link 32 connected at 33 to one arm of the bell crank lever 34 which is itself mounted for rotative movement on a pin or stud 35 and to the other arm of the bell crank lever 34 is connected a link 36, as at 37.

A bracket 38 has one arm thereof extended downwardly at 39 back of the end 40 member 4 and may be secured in place by the bolts 6. The bracket 38 extends frontwardly over the top of the end member 4 and then downwardly at 40.

The lower portion of the downwardly extending arm 40 of the bracket carries a pivotal support 41 for a toothed segment 42 herein shown as having its peripheral portion provided with teeth 43 and extending from the pivotal support 41 the segment has 45 an arm 44 pivotally connected at 45 to the link 36.

Cooperating with the toothed segment or rotatable member 42 is a detector 46 which extends downwardly from the pivotal support 41 through the upper plane of the warp threads *a* and such detector is secured to the toothed segment for movement therewith as by a screw 47, the result being that should the detector 46 be moved by engagement with 50 the fell of the cloth on the beat up movement of the lay the toothed segment or rotatable member 42 will be correspondingly moved to bring the teeth 43 thereof into engagement with the cloth *b*.

It may be desirable at times to provide

a spring 48, one end of which is connected to the toothed segment or rotatable member 42 at 49 and the other end to the downwardly extending arm 40 of the bracket 38, as at 50, the normal tendency of the spring being to 70 maintain the parts, as indicated in full lines of Fig. 1.

As more clearly shown in Fig. 2 the pivotal support 41 may be constituted as a shaft, to which the toothed segment 42 and the de- 75 tector 46 are secured.

Where the pivotal support 41 is constituted as above described it will be held for rotative movement in the bearing 51 secured to the lower end of the portion 40 of the bracket 38, as more clearly indicated in Fig. 2, and a collar 52, one at each side of the bearing 51 and secured to the shaft serves to maintain the shaft in the position indicated in Fig. 2.

During the weaving operation the detector 46 will be carried forward by the lay during its beat up movement and will engage the fell of the cloth at *c*, as indicated by dotted lines *x*, thereby causing the detector to be swung 90 about its pivotal axis, and since the detector is connected to the toothed segment 42, the latter will be turned to cause the teeth 43 thereof to engage the cloth *b*, as indicated by dotted lines in Fig. 1.

As the lay continues its frontward movement the teeth 43 of the segment will cause the latter to be further turned on its pivotal support, as indicated by dotted lines *y*, Fig. 1, thereby removing the detector 46 from the fell of the cloth into the final dotted line position *y* and permit the beat up.

As the toothed segment 42 is turned, as hereinbefore described, it will act through the link 36, bell crank 34, link 32, to turn the worm 23, thereby moving the reed in a direction from the fell of the cloth, and since the degree of movement of the toothed segment is dependent upon the position of the fell of the cloth as it is engaged by the detector 46, the amount of movement of the reed will be determined by the position of the fell of the cloth.

Should the fell of the cloth be frontward of its proper normal position due to absence of filling or loom adjustment, the detector 46 will be delayed in its contact with the fell of the cloth during the beat up and consequently the amount of movement given to the reed will be less than when the fell of the cloth is in normal position. That is to say, when the fell of the cloth is frontward of its normal position the reed will not be moved backwardly as far as it would be if the fell of the cloth were in normal position and the result is that on the beat up movement of the reed the filling or weft thread will be subjected to a uniform beat up regardless of the position of the fell of the cloth.

When the lay is in its forward position, as indicated in dotted lines, Fig. 1, it will be noted that the segment 42 has been turned to its final position, as indicated at the right of Fig. 1, and the detector 46 has been entirely removed from between the warp threads to permit the beat up of the following weft or filling thread. As the lay goes back from its front dotted line position the segment, by its engagement with the cloth, will be turned in an opposite direction and cause the detector to be again inserted between the warp threads in position to engage the fell of the cloth on the following beat up. At the same time, the segment will act through the worm to move the reed forwardly to its normal or initial position. The spring 48 may in some cases be employed to assist in returning the parts to the normal full line position when the lay is back as by the full lines in Fig. 1.

What is claimed is:—

1. In a reed positioning device for looms, the combination of the lay, a reed mounted on the lay for movement relative thereto, and means rendered operative by engagement with the fell of the cloth during beat up movement of the lay for varying the position of the reed in accordance with variations in position of the fell of the cloth.

2. In a reed positioning device for looms, the combination of the lay, a reed mounted on the lay for movement relative thereto, and means movable with the lay and rendered operative by engagement with the fell of the cloth during beat up movement of the lay for varying the position of the reed in accordance with variations in position of the fell of the cloth.

3. In a reed positioning device for looms, the combination of the lay, a reed mounted on the lay for movement relative thereto from and towards the front of the lay, and means actuated by engagement with the fell of the cloth during beat up movement of the lay for positively moving the reed relative to the lay.

4. In a reed positioning device for looms, the combination of the lay having a uniform beat up movement, a reed mounted on the lay for movement relative thereto in the direction of the lay movements, and means rendered operative by engagement of a part with the fell of the cloth during the beat up for moving the reed on the lay varying amounts determined by variations in the position of the fell of the cloth that the filling may be beaten up uniformly during weaving.

5. In a reed positioning device for looms, the combination of the lay having uniform beat up movement, a reed mounted on the lay for movement relative thereto in the direction of lay movements, and means rendered operative by engagement of a part with the fell of the cloth during beat up for positively

moving the reed to a position on the lay determined by the position of the fell of the cloth that the beat up action of the reed may be uniform.

6. In a reed positioning device for looms, the combination of the lay having uniform beat up movement, a reed mounted on the lay for movement relative thereto in the direction of lay movements, and means carried by the lay and rendered operative by engagement of a part with the fell of the cloth during beat up for positively moving the reed to a position on the lay determined by the position of the fell of the cloth that the beat up action of the reed may be uniform.

7. In a reed positioning device for looms, the combination of the lay having a uniform beat up movement, a reed mounted on the lay for movement relative thereto in a direction towards and from the fell of the cloth, means rendered operative by engagement of a part with the fell of the cloth on beat up movement of the lay for positively controlling the position of the reed on the lay and relative to the fell of the cloth that the beat up action of the reed may be uniform during weaving and operating on backward movement of the lay to return the reed to its initial position.

8. In a reed positioning device for looms, the combination of the lay, a reed mounted on the lay for movement relative thereto in a direction from and towards the fell of the cloth, means for positively controlling the position of the reed on the lay including a detector for engaging the fell of the cloth on the beat up to render said means operative to move the reed on the lay that the beat up may be uniform during weaving, said means acting on the backward movement of the lay to return the reed to its initial position.

9. In a reed positioning device for looms, the combination of the lay, a reed mounted on the lay for movement relative thereto in a direction from and towards the fell of the cloth; means for positively moving the reed on the lay to maintain uniform beat up movement of the reed, including a detector extending between warp threads into position to engage the fell of the cloth on the beat up and determine the amount of movement to be imparted to the reed by the position of the fell of the cloth.

10. In a reed positioning device for looms, the combination of the lay having a uniform beat up movement, a reed mounted on the lay for movement relative thereto towards and from the fell of the cloth that its beat up action may be varied in accordance with the position of the fell of the cloth, means carried by the lay for moving the reed relative to the lay, including a detector extending through the warp threads in position to engage the fell of the cloth during the beat up movement of the lay and connection between the

detector and reed for moving the reed an amount determined by the position of the fell of the cloth.

11. In a reed positioning device for looms, the combination of the lay having a uniform beat up movement, a reed mounted on the lay for movement relative thereto towards and from the fell of the cloth that its beat up action may be varied in accordance with the position of the fell of the cloth, means carried by the lay for moving the reed relative to the lay, including a detector extending through the warp threads in position to engage the fell of the cloth during beat up movement of the lay, a rotatable member which is moved into engagement with the cloth by the detector, and connections between the rotatable member and reed for moving the latter on the lay an amount determined by the position of the fell of the cloth.

12. In a reed positioning device for looms, the combination of the lay, a reed mounted on the lay for movement relative thereto in a direction towards and from the fell of the cloth that its beat up action may be maintained uniform under variation in position of the fell of the cloth, means carried by the lay for varying the position of the reed including a detector adapted to engage the fell of the cloth on beat up movement of the lay, a connected rotatable member having projections which are moved into engagement with the cloth by the detector, and connections between the rotatable member and reed for moving the latter an amount determined by the position of the fell of the cloth.

13. In a reed positioning device for looms, the combination of the lay, a reed mounted on the lay for movement relative thereto in a direction towards and from the fell of the cloth, a detector carried by the lay and positioned to engage the fell of the cloth on beat up movement of the lay, a connected segment having projections which are initially moved into cloth engaging position by the detector and thereafter act during the beat up to turn the segment and cause removal of the detector from the fell of the cloth, and connections between the segment and reed for moving the latter.

14. In a reed positioning device for looms, the combination of the lay, a reed mounted on the lay for movement relative thereto in a direction towards and from the fell of the cloth, a detector carried by the lay and positioned to engage the fell of the cloth on beat up movement of the lay, a connected segment having projections which are initially moved into cloth engaging position by the detector and thereafter act during the beat up to turn the segment and cause removal of the detector from the fell of the cloth, a worm movable with the lay, an arm connected to the reed and engaging the worm, and connec-

tions between the segment and worm for turning the latter and moving the reed relative to the lay.

In testimony whereof, I have signed my name to this specification.

LLOYD L. DAVIS.
